Samuel W. Gibbs of Albany N.Y.

Assignor to

Thinner & Brothers of Brownville N.Y.

Letters Patent No 713 Dated June 26. 1835

The Schedule referred to in these Letters Patent and making part of the same

Be it known that I Samuel W. Gibbs of the City of Albany State of New York have invented a new ornamental Design for the plates of a Cooking Stove, called the Fashion Stove; and I declare the annexed Drawings to be full and accurate descriptions of the ornamented plates with their several ornaments, the side plates (a pair) being shown by the one at Figure 1. and the door plates (a pair) being shown by the one at Figure 2. and the oven front plate being shown by Figure 3.

What I claim as my production and desire to secure by Letters Patent is the combination and arrangement of ornamental figures and forms represented in the accompanying drawings forming the ornamental Design for the plates of a Cooking Stove
